GENERATOR VENTILATOR

Louis A. Koch, Jr., Louisville, Ky.

Application June 14, 1934, Serial No. 730,653

8 Claims. (Cl. 171—252)

The present invention relates to dynamo electric machines, more especially dynamos for use on self propelled vehicles equipped with means for circulating air to be employed in connection with units contributing to the operation thereof.

The main object is to provide for ventilation of the dynamo in order to increase the volt ampere output without reconstructing or even removing same from a vehicle.

10 A further object consists of collecting a portion of the circulated air, cleaning and directing it into the generator and thereby force air from within the generator that has been heated as a result of the operation of said generator.

15 Another object is to provide a simple effective integral equipment to convert the dynamo from a closed to a forced draft ventilated machine by means of a minimum outlay of material, labor and money.

20 Examples of the incident invention are illustrated in the accompanying drawing.

Drawing

Figure 1 is a side elevational view of a portion 25 of a generator housing equipped with my generator ventilator.

Fig. 2 is a front elevational view of Fig. 1.

Fig. 3 is a side elevational view taken from the reverse side of Fig. 1.

30 Fig. 4 is a cross sectional view of an enlarged scale of a section taken through that portion of Fig. 2 adjacent the arrow A and on the line as indicated.

Fig. 5 is a front elevational view of a modification of Fig. 2.

Fig. 6 is a side elevational view of Fig. 5, also a section of the end of the generator housing on which it is located.

Structure

40 Numeral 10 represents a section of a shell, housing or field frame construction of a dynamo electric machine, such as a generator employed on automotive vehicles for supplying current for the 45 operation of electrical appurtenances carried thereon.

11 indicates hand hole openings or "windows" in the housing and 12 represents a flexible band frequently termed a "window strap", a portion 50 of the surface of which has been opened and shaped to form a series of diagonally disposed louvers 13, while another portion of the surface has been opened to produce an inlet aperture 14, the perimeter of which is projected upwardly to 55 form a collar 14A as shown in Fig. 4. Immedi-

ately adjacent, and largely surrounding this aperture, funnelled hood 15 has been attached. The front or open end of this hood has been equipped with a filter medium 16 reinforced with coarse wire mesh 17. It will be noted that the hood has been so constructed that the exposed surface of the filter medium will repose on an angle to the perpendicular and that the lower edges of the medium have been lodged outside of the collar 14A in order that entrained water 10 will be arrested by the filter where it will trickle downward in response to gravity and drain off the outer surface of the strap, where it cannot damage the interior of the dynamo. Another portion of the window strap 12 has been pressed 15 to form a series of cups 18 to receive the ends of latch 19. The object of this being to provide not only a latch but means for adapting the strap to various diameters of housings without the use of tools or other devices. The aforescribed 20 structure represents a preferred form of my "generator ventilator".

Ordinarily the generator is supplied from the manufacturer with a cover strap without openings and serves only as a closure for openings 11. 25 It is a simple procedure, frequently involving only a minute or two, to substitute my generator ventilator for the old strap and thereby instantly provide means for a dependable supply of filtered fresh air which enables the generator to safely 30 carry an increased volt ampere load.

In Figs. 1 and 6 the group of arrows B are shown to indicate a stream of air coming from a radiator cooling fan as is commonly found on self propelled vehicles. Again these arrows may 35 be regarded as also representing a stream of air created by the movement of the vehicle. This portion of the air stream can be regarded as the windward side when viewed from the mouth of hood 15. The other group of arrows indicate 40 the air leaving the generator. A portion of the air stream longitudinally traversing the exterior of the generator is diverted by louver 15, or its equivalent, into the interior of the generator housing, and is forced across the commutator and brushes and then out of the generator via openings 13 or 22 thereby producing effective cooling 45 for such parts that are normally subjected to relatively high temperatures. Thus it will be perceived that a steady change of air will be 50 effected within the dynamo, while the vehicle on which it is installed is in operation. Attention is directed to the fact that the force of the air stream exerts pressure on the interior of the generator while another portion of said stream in 55

passing over the diagonal louvers 13 ejects or sucks air from said interior.

Modification

- 5 The flexible strap 12 has been made with two groups of louvers 13, one set as shown in Figs. 1 and 2, while the other group was reversed, i. e. the openings were turned to windward (not illustrated).
- 10 In Figs. 5 and 6 a shell 20, has been employed in place of the band or strap 12 in the former figures. It has been so fashioned that it fits entirely over the end of the housing 10 so as to cause the openings of the housing to register with those of the shell. The hood 21 is substantially the same as hood 15, although different in proportions. Small cupped hoods 22 are shown attached to the shell with their openings directed to leeward so as to enable them to function similarly to the method given in connection with louvers 13. These cups 22 have been formed with an arcuate base to enable them to conform to the contour of rigid shell 20, which is at variance to the structure shown in Fig. 1, where it was 25 highly desirable to maintain the flexibility of strap or band 12, and at the same time utilize the air stream to function in connection with the openings of the louvers to produce a siphoning effect and thereby eject air from the interior 30 of housing 10.

This application is a development from the principles disclosed in my co-pending application, No. 641,481, filed November 1932.

Still further developments and modifications 35 can and have been made without departing from the spirit of this invention, therefore, I wish to be limited only by the attached claims.

I claim:

1. Means for cooling a dynamo, having associated therewith a stream of air, comprising a dynamo having a substantially closed housing, hand hole openings in the housing, a flexible band encircling said openings, said band being equipped with a funnelled opening positioned to windward in said stream of air so as to divert a portion of same into the dynamo, said band also being equipped with an opening positioned to leeward in said stream, thereby producing a siphoning effect on the air within said housing.
- 40 2. Means for cooling a dynamo, having associated therewith a stream of air, comprising a dynamo having a substantially closed housing, hand hole openings in the housing, a flexible band encircling said openings, said band being 45 equipped with a series of diagonal openings positioned to windward in said stream of air so as to divert a portion of same into the dynamo, said band also being equipped with another series of openings positioned to leeward in said stream, thereby producing a siphoning effect on the air within said housing.
- 50 3. Means for cooling a dynamo, having associated therewith a stream of air, comprising a dynamo having a substantially closed housing, 55 hand hole openings in the housing, a member encircling said openings, said member being equipped with an opening positioned to windward in said stream of air so as to divert a portion of same into the dynamo, said member also being 60 equipped with an opening positioned to leeward in said stream, thereby producing a siphoning effect on the air within said housing.

4. Means for cooling a dynamo, having associated therewith a stream of air, comprising a dynamo having a substantially closed housing, hand hole openings in the housing, a flexible band encircling said openings, said band being fashioned with an outwardly flanged opening, the latter having associated therewith a hood which with a portion of said band forms an open mouth, an air filter medium lodged in said mouth, said mouth being positioned to windward in said stream of air so as to divert a portion of same into the dynamo, said band also being equipped with an opening positioned to leeward in said stream, thereby producing a siphoning effect on the air within said housing.

5. Means for cooling a dynamo, having associated therewith a stream of air, comprising a dynamo having a substantially closed housing, hand hole openings in the housing, a member encircling said openings, said member being fashioned with an opening, the latter having associated therewith a hood which with a portion of said member forms an open mouth, an air filter medium lodged in said mouth, said mouth being positioned to windward in said stream of air so as to divert a portion of same into the dynamo, said member also being equipped with an opening positioned to leeward in said stream, thereby producing a siphoning effect on the air within said housing.

6. Means for cooling a dynamo, having associated therewith a stream of air, comprising a dynamo having a substantially closed housing, hand hole openings in the housing, a flexible band encircling said openings, said band being fashioned with an opening, the latter having associated therewith a hood which with a portion of said band forms an open mouth, an air filter medium lodged in said mouth, said mouth being positioned to windward in said stream of air so as to divert a portion of same into the dynamo, said band also being equipped with an opening positioned to leeward in said stream, thereby producing a siphoning effect on the air within said housing.

7. In combination with a dynamo having an air stream associated therewith, the housing of same being provided with holes therethrough, a detachable member associated with said holes, said member being equipped with a louver, said louver being open to the atmosphere only on one side and organized to cooperate with said air stream and conduct a portion of same to the interior of said dynamo, said member also being equipped with an outlet opening in communication with said holes and the interior of the dynamo.

8. In combination with a dynamo having an air stream associated therewith, the housing of same being provided with holes therethrough, a detachable member associated with said holes, said member being equipped with a louver, said louver being open only on one side and organized to conduct a portion of said air stream to the interior of said dynamo, said member also being equipped with an outlet opening to establish communication between the atmosphere and the interior of the dynamo via said holes, said air stream cooperating with said louver to force an exchange of air within the housing for external air.
